UNITED STATES PATENT OFFICE

138,690

DESIGN FOR A WALL INTERIOR EXPLORING AND EXAMINING DEVICE

Clarence B. Downing, Milford, Del.

Application June 14, 1944, Serial No. 113,988

Term of patent 14 years

(Cl. D57—1)

To all whom it may concern:

Be it known that I, Clarence B. Downing, a citizen of the United States, residing at Milford, in the county of Sussex and State of Delaware, have invented a new, original, and ornamental Design for a Wall Interior Exploring and Examining Device, of which the following is a specification, reference being had to the accompanying drawings, forming part thereof.

Figure 1 is a top plan view of a wall exploring and examining device showing my new design.

Figure 2 is a side elevation thereof.

Figure 3 is a front elevational view looking into the article from the right of Figure 2.

Figure 4 is a perspective view.

I claim:

The ornamental design for a wall exploring and examining device as shown.

CLARENCE B. DOWNING.
